UNITED STATES PATENT OFFICE.

CHARLES R. BIRDSEY, OF HINSDALE, ILLINOIS, ASSIGNOR, BY MESNE ASSIGNMENTS, TO UNITED STATES GYPSUM COMPANY, OF CHICAGO, ILLINOIS, A CORPORATION OF ILLINOIS.

PLASTER-BOARD.

1,395,032.

Specification of Letters Patent. Patented Oct. 25, 1921.

Application filed January 2, 1920. Serial No. 348,942.

To all whom it may concern:

Be it known that I, CHARLES R. BIRDSEY, a citizen of the United States, residing at Hinsdale, in the county of Du Page and 5 State of Illinois, have invented certain new and useful Improvements in Plaster-Board, (Case D,) of which the following is a description.

My invention belongs to that general 10 class of devices known as plaster board or the like and relates particularly to a type of board in which the plaster, plaster Paris or equivalent plastic material is substantially inclosed on both faces and on one or 15 both opposite edges. The invention has among its objects the production of an improved board, which will be simple, substantial, durable, satisfactory and efficient and which may be economically and accurately manufactured, and in which the 20 edges may be perfectly formed to correspond to a definite specification as to size and shape. Many other objects and advantages of the construction herein shown and described will be obvious to those skilled 25 in the art from the disclosure herein given.

To this end my invention consists of the novel construction, arrangement and combination of parts herein shown and described 30 and more particularly pointed out in the claims.

In the drawings, wherein like reference characters indicate like or corresponding parts,

35 Figure 1 is a sectional view through a portion of a plaster board embodying the invention,

Fig. 2 is a perspective view of a portion of the same board,

40 Fig. 3 is a similar view of a slightly modified construction,

Fig. 4 is a sectional view of a portion of a board illustrating a further step in the construction, and

45 Fig. 5 is a view similar to Fig. 2 of another form of board.

Referring to the drawings, particularly Figs. 1 and 2, 1 represents a board of suitable material, as for example, plaster, plaster Paris, or any equivalent material suitable for the purpose which may be handled in a plastic state and thereafter allowed to set or harden. The body is inclosed by the covering sheets 2 and 3 of suitable ma-

terial and it may be mentioned that I have 55 found paper of the desired weight or thickness very satisfactory for the purpose.

In the type of board illustrated in Figs. 1 and 2 I inclose the one or both side edges by a binder or strip 5 which covers the 60 edge of the board and is folded inwardly, as at 6 and 7, to overlie the two opposite sides of the faces of the board. The same is preferably scored at 8 before folding, so as to give a straight or regular edge, the 65 contour of the edge being as desired. In constructing the board, I preferably seal the same by allowing a portion of the plastic body to flow in between the faces of the sheets 2 and 3 and the folded-in edges 6 70 and 7, as indicated at 9. Any equivalent means for securing the folded-in edges to the covering sheets 2 and 3 may be employed.

In the construction shown in Fig. 3, the 75 edge binder is similar to that described except that it is constructed to overlie the body but on the exterior of the covering sheets 12 and 13. Referring to this figure, 11 represents the body and 12 and 13 the 80 covering sheets, while 15 represents the binder having the extending folded-over edges 16 and 17, the same being preferably scored as at 18. In this case the same is sealed between the covering sheets as indicated at 19. In Fig. 4 it is illustrated how the parts may be so pressed or so formed that the folded-over edges 16 and 17 will be substantially flush with the exterior faces of the covering sheets 12 and 13. 90

In the construction shown in Fig. 5, 21 represents the body and 22 and 23 the covering sheets. In this construction 25 represents the edge binder which is folded over as at 26 so as to overlie the body, the same 95 being positioned on the exterior, as shown, or on the interior side of the covering sheets, as may be desired. The binder is preferably first scored as at 28, or folded so as to produce a comparatively uniform edge. The 100 edge 27 of the binder 25 may engage with the sheet 22, as shown, or at the edge.

It will be noted that with all of the constructions described, the edge is substantially completely inclosed which, as before mentioned, may be at one or both sides. Obviously, if the sheets were integral and wrapped over one edge, then only one edge 105

would need to be inclosed. The resulting product has a straight, smooth, finished edge and at a perfect angle, the board being uniform in width throughout its length. The 5 completed product has many advantages and it has increased strength and durability and an improved appearance. In case of handling the edges are protected and there is no sifting or powdering of the body or 10 breaking away of the edge.

Having thus described my invention, it is obvious that various immaterial modifications may be made in the same without departing from the spirit of my invention; 15 hence I do not wish to be understood as limiting myself to the exact form, construction, arrangement and combination of parts herein shown and described or uses mentioned.

20 What I claim as new and desire to secure by Letters Patent is:

1. A plaster board comprising a suitable body, a cover sheet arranged on each face thereof, and an edge binder strip at one edge 25 of the body folded to overlie the body at each face thereof, the cover sheet and edge binder portion on each face of the body being arranged to present a substantially con-

tinuous even outer face throughout the outer face of the board.

2. A plaster board of the kind described, comprising a suitable body, a cover sheet arranged at each face side thereof, and an edge binder arranged at each of the opposite edges and adhering thereto, said binder 35 folded in to overlie the body at the interior of the cover sheets.

3. A plaster board of the kind described comprising a suitable body, a cover sheet arranged at each face side thereof, and separate edge binder strips at opposite edges folded to overlie the body at each face side thereof, and separate edge binder strips at opposite edges folded to overlie the body at each face thereof, the cover sheet and 45 edge binder strip portion on each face of the body being arranged to present a substantially continuous even outer surface throughout the outer faces of the board.

In testimony whereof, I have hereunto 50 signed my name in the presence of two subscribing witnesses:

CHARLES R. BIRDSEY.
